UNITED STATES PATENT OFFICE.

RUSSELL B. SMITH, OF NEW YORK, N. Y.

METHOD OF BUILDING REINFORCED-CONCRETE SHIPS.

1,373,267.

Specification of Letters Patent. Patented Mar. 29, 1921.

Application filed September 20, 1918. Serial No. 254,984.

To all whom it may concern:

Be it known that I, RUSSELL B. SMITH, a citizen of the United States, whose post-office address is 50 East Forty-second street, 5 New York, New York, have invented an Improvement in Methods of Building Reinforced-Concrete Ships, of which the following description, in connection with the accompanying drawings, is a specification, 10 like letters on the drawings representing like parts.

The present invention relates to concrete ship construction wherein reinforcing metallic members are employed, and to a novel 15 method of building the same. The objects of the invention are to improve and perfect the building of reinforced concrete ship construction, to economize time, labor and material, to employ in an advantageous manner a cement gun, to apply the concrete directly on the reinforcing metal, and to provide a strong, durable, and serviceable ship or vessel of reinforced concrete.

The advantages of reinforced concrete for 20 ship construction have been established and are now well known and in my present invention I arrange the building of the reinforcing metal work so that the same will be self-sustaining, eliminating the use of 25 molds and other temporary framework of this sort, and including sufficiently fine wire mesh or lath so as to receive and hold the concrete as it is applied directly thereto by means of a cement gun. To this end, I first 30 build up the reinforcing framework as a fabricated unit of sufficient strength to be self-sustaining and of sufficient thickness and fineness to receive and hold the concrete and then "shoot" the concrete thereon from 35 either or both sides of the desired thickness. 40

I am enabled to carry out this process of ship construction in an economical and advantageous manner by utilizing a novel type of removable supporting and alining 45 chair and construction explained in my co-pending application, Serial No. 254,983 filed September 20, 1918. With this alining chair, I can prepare the ways and temporary blocking for the ship, applying a small number of horizontal and vertical stringers or 50 supports to which these removable chairs are affixed, then building up the metal reinforcement upon these alining and supporting chairs, thus securing a metal reinforcement—preferably including one or more con-

crete-receiving metal meshes and reinforcing bars—formed together in self-sustaining position, thereupon removing a suitable section of the stringers and chairs, leaving the inner metal framework for this section 60 exposed for "shooting", replacing temporary blocking in the completed section and preparing and "shooting" the adjacent section.

Although it may be desirable to remove 65 the alining and supporting chairs so that the same may be used repeatedly, it will be understood that I can also include these chairs permanently as a part of the metal reinforcement and apply the concrete covering over the inner metal structure.

It is, I believe, entirely new to utilize 70 a member such as my type of supporting and alining chair in ship construction, employing such chairs to position, hold, and 75 aline the various reinforcing instrumentalities, such as meshes, bars, etc., holding them until they are independently secured together, which chairs can be either left in permanently or removed, and this feature is 80 of particular importance in my present method of ship construction.

Great speed in construction is possible 85 with the present invention, the arrangement of the alining chairs on supports along the bottom of and the sides of the ship being all the framework necessary and these chairs being applied on spaced stringers or scantlings, whereupon the metal mesh and reinforcing bars are automatically alined by 90 applying the same over and through the supporting chairs. These metal reinforcing members being at once wired or secured together so that the structure is immediately 95 self-sustaining and no very material strain is placed upon the chairs or their supports. If it is desired to remove the chairs for future use, they may be secured to the scantlings or stringers and removed by the removal of the scantlings, after the framework is wired together and a section is prepared for "shooting" the concrete. In a ship of 150 to 300 feet in length, I find that it is possible to assemble the entire metal framework in approximately one week, applying 100 the concrete thereto in a continuously "shooting" operation by removing the scantlings in 12 to 15 foot sections successively, in a second week, and thereafter allowing 105 the concrete to cure in from 10 days to 2 110

weeks and the vessel is complete. Meanwhile the scantlings and attached chairs—in case these are removed,—can be set up in the fabrication of a second ship. It will be understood that just prior to the "shooting" of the concrete, I would apply and position the various protecting corner pieces, stem and stern sections, bolts, coamings, for sides and decks, as is customary. My 10 method eliminates all the prior work heretofore necessary in the building of a complete mold for the ship,—particularly difficult around the curved contours at stem and stern of a standard ship model—saving the labor and material therefor and eliminating the old process of pouring and tamping down the concrete and enabling a more rapid and efficient method of "shooting" to be employed advantageously. The alining 15 chairs I use and the fabrication of the wire mesh or meshes and reinforcing rods, can be easily and readily conformed to the uneven contours of a ship model, carrying out said model perfectly and easily, insuring 20 that the cement applied thereto will also complete the model desired. By using a cement gun also, the layers of concrete are more uniformly applied to each side of the reinforcing, the latter being accurately centered 25 in the mass of concrete and covered to any depth.

Referring to the drawings illustrating the preferred construction, in accordance with my present method;

35 Figure 1 is a view in perspective of my novel type of supporting and alining chair;

Fig. 2 being a fragmentary view partly in cross section, showing the chair in use; and

40 Fig. 3 being a fragmentary midship half section, illustrating the present method of construction.

As described in my said co-pending application and as illustrated in Fig. 1, my alining and supporting chair is so made as 45 to support and position the wire mesh to constitute a concrete-receiving portion of the reinforcement, on one set or plurality of members, *i. e.* the horizontal members, and to have a plurality of members at right 50 angles thereto, *i. e.* extending vertically, passing through the wire mesh and arranged in spaced pairs to hold and position any additional strengthening and reinforcing members, such as a second wire mesh and 55 bars or rods. This supporting and alining chair, I have described generally as at A and the same as herein shown comprises a member 1 carrying the vertically extending members 2, 3, 4, and 5 and horizontally extending members 6 and 7. These horizontal 60 members 6 and 7 may be recessed as indicated at 8—8 or otherwise prepared to interlock with the wire mesh applied thereto, such as the well-known Hy-Rib type 65 wherein the depending rib of the mesh

would fit within the recesses 8 of these members. I may also lighten these members by forming the same with the recesses 10—10 in the members 6 and 7 and 12 in the member 1, if desired, particularly when the chairs are intended to be left within the concrete as a part of the permanent reinforcement, thus allowing the concrete to flow there-around and interlock more firmly therewith. As shown in Fig. 2, the chairs A 75 may be positioned in a plurality of ways to support the fine mesh or Hy-Rib indicated at 15 and a second heavier wire mesh, for example, a second wire lath, such as the wellknown Kahn mesh 16 and with the upright members 2, 3, 4, and 5 spacing and alining the heavier reinforcing bars 17, throughout the exterior walls or planking of the ship. These chairs may be of any suitable size for the particular work in hand. I can also employ these chairs as a basis for building up concrete ribs or keelsons, as indicated at B—B. These chairs being positioned at right angles to the others just described and with equal efficiency, the 80 Hy-Rib 16 resting on the same, and heavy crossbars 18 constituting the reinforcements for the concrete ribs 20 being fitted there-through. In this construction the bars 17 may be deflected to extend over the reinforcing rods 18 and give an additional form of truss-like construction. A suitable wire mesh 21 to complete the reinforcement of the ribs 20 would be prepared, all the metal reinforcement being wired together at suitable points, as indicated at 25—25. If it is desired to include the chairs as a part of the 85 permanent structure, then the same would be also included in the wiring as indicated at 26, but if it is desired to remove the chairs, then the same would be wired or otherwise secured to the stringers or scantlings 30, removal of these scantlings, in preparation for the "shooting," automatically withdrawing these chairs as they are 90 free to be disconnected from the metal framework, unless wired thereto.

I have indicated generally the line of supports or scantlings 30, illustrating the very small extent of the framework necessary in 95 my present method of reinforced concrete ship construction. When these scantlings are removed in suitable sections, 6 to 15 feet lengthwise of the ship and from gunwale to gunwale, the concrete is then applied to the 100 entire section and built up to any suitable thickness, such for example as indicated between the lines 32 and 33 and around the ribs 20. In forming such ribs 20 additional bars and wiring as indicated at 35 may be 105 employed for further strength, uniting the same with additional reinforcing members 36 at corners or for points where further braces are necessary.

110 My novel method of ship construction thus 115

enables a reinforced concrete structure to be formed quickly, economically, and with great speed. By building up the unit framework, a minimum of metal is employed and yet 5 this metal is all assembled in exactly the reinforcing position it is desired, it shall take in the completed concrete coating. The positioning of the scantlings and alining chairs thereon automatically determines the position 10 and alinement of the reinforcing metal, holding said reinforcing metal members in exactly proper position, for strength, and to receive the concrete as applied from a cement gun. The many advantages incident to this 15 method of construction will readily be appreciated by those skilled in the art and a strong, durable reinforced concrete ship is produced.

My present invention is further described 20 and defined in the form of claims as follows:

1. The method of reinforced concrete ship construction which consists in placing supporting and alining chairs at spaced intervals on supports, applying a concrete-receiving 25 and retaining metal mesh to said chairs, placing reinforcing bars temporarily in alinement by said chairs, securing the re-

inforcing metal together into a self-sustaining unit framework, removing the supports for a predetermined section, applying concrete to the framework, replacing supports under said concreted section and preparing the adjacent section for the application of concrete and continuing the same until completed.

2. The method of reinforced concrete ship construction which consists in placing supporting and alining chairs at spaced intervals on supports, applying a concrete-receiving and retaining metal mesh to said chairs, 40 placing reinforcing bars temporarily in alinement by said chairs, securing the reinforcing metal together into a self-sustaining unit framework, removing the supports for a predetermined section, applying concrete 45 to the framework, and replacing the supports under said concreted section.

In testimony whereof, I have signed my name to this specification, in the presence of two subscribing witnesses.

RUSSELL B. SMITH.
